UNITED STATES PATENT OFFICE.

LINDON WALLACE BATES, OF MOUNT LEBANON, NEW YORK.

METHOD OF PROTECTING SHIPS.

1,379,241.

Specification of Letters Patent.

Patented May 24, 1921.

No Drawing.

Application filed February 19, 1920. Serial No. 359,911.

To all whom it may concern:

Be it known that I, LINDON W. BATES, a citizen of the United States, and resident of Mount Lebanon, in the county of Columbia 5 and State of New York, have invented certain new and useful Improvements in Methods of Protecting Ships, of which the following is a specification.

This invention pertains to a method of 10 protecting vessels from the explosive effects of torpedo and gun fire as well as internal explosions. More particularly it pertains to the transformation by cold of liquid or mobile fuel carried by such vessel in its fuel 15 tanks into a solid or semi-solid body. The preferred fuel is described in detail in my copending application, Serial No. 315,497, filed August 5th, 1919, directed to a "fuel and method of producing same." This fuel 20 is a stable composite comprising pulverized carbonaceous substance and liquid hydrocarbon treated and controlled by the use of certain stabilizing substances such as lime-rosin grease or coal distillates having peptonizing qualities, or equivalent stabilizing substances. But the congealing method herein 25 described may be used with other liquid or mobile fuels than the fuel called colloidal fuel above mentioned. Furthermore it is 30 not necessary to the application of this method that the fuel be stable, although for use as fuel it needs the stability feature at normal temperature. The utility of the fuel 35 is not affected by the congealing treatment. Broadly speaking, all mobile fuels may be utilized for defensive purposes on shipboard which are subject to congelation.

It is known in military science that aside 40 from armor plating, sand and asphalts are among the substances most difficult for projectiles to penetrate and cause damage on explosion. The oil tanks and coal bins on ships are now purposely located in such 45 positions as to serve in some measure the protective purpose. But oil is an inflammable liquid and is easily traversed by a shell. An oil fire cannot be extinguished by water. The lumps of coal in a bin offer some resistance 50 to the passage of the shell and the transmission of explosive forces, but afford much less resistance than sand or even than coal in finely pulverized form. On the other hand colloidal fuel is not affected by sea 55 water and may carry in stable suspense in liquid form up to about 40% by weight of

carbonaceous particles and in mobile paste form still higher percentage. This fuel lends itself readily to special congealing or freezing treatment which hardens it to a material and adequate extent to produce a solid or semi-solid wall, asphalt-like in its appearance and operation. The fuel can readily be again liquefied and used, but while partially or wholly congealed serves 60 in effect as a thick armor plate protecting the interior of the ship. This is the first instance of the application of cold to a liquid fuel or to any other fuel for military ends. 65

To illustrate the hardening efficiency of 70 colloidal fuel, the results of certain tests are instructive. A typical fuel of this class contains 36.4% by weight of coal particles and coke particles mixed, in Mexican reduced oil, stabilized with 1.5% of lime-rosin 75 soap carried in 8.5% of fuel oil. At 70° F. its viscosity, when five months old, is 3168° Engler. Its viscosity, when first made, before the gel formation has begun, is considerably less. At 32° F. the fuel is much 80 more viscous than at ordinary temperatures. The material still possesses the ability to flow as a liquid, but very slowly. At 23° F. the thickening process has progressed to such an extent that there is practically no 85 evidence of flowing. At -13° F. the fuel loses all resemblance to a liquid and assumes that of a thick paste. It is not possible to cause the material to flow at this temperature. At -4° F. it has a penetrability of 90 340 and at -67° F. of 290. These numbers represent the distance in millimeters penetrated by a No. 2 needle weighing 100 grams in five seconds. A penetration of 290 is 95 about the consistency of material of a stiff graphite paste or the consistency of a soft road binder of asphalt cement.

It is not necessary to transform the fuel 100 into a solid in order to use it as a protection against shell fire and explosion. It is better for it to be sufficiently paste-like to fill cavities under its own pressure after a shell has passed through a tank or exploded therein. The amount of congealing may be 105 regulated according to the duties to be performed and hardness desired. The word "congealing" is used to signify lowering of temperature irrespective of actual freezing or solidifying.

The use of elaborate mechanism to congeal the fuel is not necessary as insulation 110

of the tanks preserves low temperature. The principle of the thermos bottle may be employed. Any suitable mechanism and method of congealing may be utilized. On ship-
5 board the use of brine or carbonic acid for cooling purposes is favored. Pipes are laid in the chamber to be cooled, usually in the form of a grid or coil, sometimes on the side, sometimes overhead, sometimes in
10 the center, sometimes between two tanks. In the first method, brine is kept in circulation in the pipes. The brine may consist of salt water, not sea water but water in which common salt has been
15 dissolved, but more often consists of a solution of chlorid of calcium. Dissolving a substance in water lowers the freezing point of the solution. A 20% calcium chlorid solution lowers the freezing point to 5° F.
20 The use of a liquid that freezes at temperatures below that at which the product is to be held is necessary in this freezing method. When carbonic acid is used a compression machine and other apparatus are required,
25 to reduce the acid to a liquid state in which condition it is conveyed to the expansion coils. The anhydrous liquid on passing into the extension coils is suddenly released from the pressure under which it is held and is
30 thereby reformed into gas. As a liquid can only become a gas by the addition of heat, it absorbs the heat from the surrounding objects, in this case from the fuel to be congealed. ("Cold Storage, Heating and Ventilating on Board Ship," S. F. Walker, R. N.,
35 1911.) There are numerous other ways of adequately cooling mobile fuel in storage tanks. It is desirable to be able to use the pipes or coils both for heating and cooling
40 purposes.

Congealed fuel may be restored to desired fluidity by heat. Thus the colloidal fuel mentioned earlier has a fluidity of 29.8° Engler at 200° F. and 11.3° Engler at 230°

45 F. The fuel is not injured by such cold storage, no matter how prolonged. When fluidified again the fuel takes up its life where it left off upon congealing. Brownian activity resumes in full strength. The period of
50 stability assured by the stabilizing treatment begins again to run, and if before congealing the fuel still has a couple of months' life ahead, after decongealing it will still have this time of assured stability before it. No
55 material change in the fuel results from the application of this storage method, as regards usefulness.

The congealing of the fuel serves not only the military defensive purpose but it also
60 prevents or hinders change in the physical state of the fuel, such as separation of the particles from the liquid dispersion medium. By so prolonging the life of a fuel the particles in a short lived fuel need not be re-
65 duced to so fine a size. The cold storage

has also a fire hazard value. It takes a longer application of heat or more heat to ignite congealed fuel than fuel at normal temperatures. So also the fuel may be stored under a water seal, the water being 70 liquid or ice. This may also be done in the case of a stable mobile fuel irrespective of congealing. When a projectile penetrates a tank containing congealed colloidal fuel the heat causes the fuel adjacent to the path of 75 the projectile to flow and to plug the hole. The congealing effect of the surrounding fuel and its pressure will serve to again present a comparatively unbroken wall to further projectiles and to the admission of sea 80 water.

The composition of the fuel may be regulated to render it more solid or more liquid at given temperatures. Thus wax tailings and pitches are solid up to a certain temperature and then melt suddenly under heat. If small percentages of such substances are added to the colloidal fuel on manufacture, the fuel will be more solid or gel-like at low temperatures, and yet will flow about as well 90 as before when heated for atomization and use as fuel.

It is also possible to increase the defensive efficiency of congealed fuel by varying the viscosities in the several tanks. There are 95 usually several layers of these tanks, or a honeycomb structure. An outside tank may be made to contain solid fuel, and an inner one paste-like fuel, and other tanks fuel of viscosity between these two or otherwise. A 100 projectile is held up to a greater extent by passing through bodies of varying consistency than by passing through bodies of uniform character. This principle may be applied in various ways on shipboard. Certain of the military aspects of this new art are reserved for presentation on another occasion, in applications divisional by nature. 105

Having thus stated the nature of my invention, what I claim is:

1. That method of protecting a vessel using mobile fuel comprising particles of carbonaceous substance and liquid hydrocarbon against shell or torpedo fire, which consists in congealing the fuel while in storage on the vessel and maintaining it so congealed. 110

2. That method of protecting a vessel using mobile fuel comprising particles of carbonaceous substance and liquid hydrocarbon against shell or torpedo fire, which consists in increasing the viscosity of the fuel while in storage on the vessel by the application of cold until a thick paste is obtained and maintaining such consistency by 115 cold.

3. That method of protecting a vessel using mobile fuel comprising particles of carbonaceous substance and liquid hydrocarbon against shell or torpedo fire, which 120

130

5 consists in lowering the temperature in the tank on the vessel containing the fuel until the fuel approaches a semi-solid in consistency and maintaining such condition by congelation.

4. That method of protecting a vessel using mobile fuel comprising particles of carbonaceous substance and liquid hydro-carbon against shell or torpedo fire, which 10 consists in bringing the fuel to a temperature below 40° F. in storage on the vessel and maintaining such temperature.

5. That method of protecting a vessel using mobile fuel comprising particles of 15 carbonaceous substance and liquid hydro-carbon against shell or torpedo fire, which consists in applying cold to the fuel which lowers and maintains its temperature at approximately 0° F. whereby the fuel becomes 20 semi-solid and forms in the tank a protective wall defending the interior of the vessel.

6. That method of protecting a vessel using mobile fuel comprising particles of 25 carbonaceous substance and liquid hydro-carbon against shell or torpedo fire, which consists in congealing the fuel while in storage on the vessel and maintaining it so congealed, and thereafter preheating the 30 said fuel until it flows when use is desired.

7. That method of protecting a vessel using mobile fuel comprising particles of carbonaceous substance and liquid hydro-carbon against shell or torpedo fire, which 35 consists in increasing the viscosity of the fuel while in storage on the vessel by the application of cold until a thick paste is obtained and maintaining such consistency by cold, and thereafter restoring the former 40 state by heat so that the fuel may be utilized as such.

8. That method of protecting a vessel using mobile fuel comprising particles of carbonaceous substance and liquid hydro- 45 carbon against shell or torpedo fire, which consists in congealing the fuel while in storage on the vessel and maintaining it so congealed by passing a freezing mixture through a coil or equivalent freezing apparatus 50 associated with the storage tank, and thereafter passing steam through a coil or equivalent heating apparatus associated with the said tank to fluidify again the fuel for use as such.

9. That method of protecting a vessel 55 using mobile fuel comprising particles of carbonaceous substance and liquid hydro-carbon against shell or torpedo fire, which consists in congealing the fuel while in storage on the vessel and maintaining it so congealed, and storing the fuel under a water seal which forms a layer adjacent to the top surface of the fuel and in contact therewith.

10. That method of protecting a vessel 60 using mobile fuel comprising particles of carbonaceous substance and liquid hydro-carbon against shell or torpedo fire, which consists in bringing the fuel to a temperature below 40° F. in storage on the vessel and maintaining such temperature, and storing the fuel under a water seal which forms a layer adjacent to top surface of the fuel and in contact therewith.

11. That method of protecting a vessel 65 using mobile fuel comprising particles of carbonaceous substance and liquid hydro-carbon against shell or torpedo fire, which consists in increasing the viscosity of the fuel while in storage on the vessel by the 70 application of cold until a thick paste is obtained and maintaining such consistency by cold, and thereafter restoring the former state by heat so that the fuel may be utilized as such, and during these operations 75 storing the fuel under a water seal which forms a layer adjacent to the top surface of the fuel and in contact therewith.

12. That method of protecting a vessel 80 using mobile fuel comprising particles of carbonaceous substance and liquid hydro-carbon against shell or torpedo fire, which consists in congealing the fuel while in storage on the vessel and maintaining it so congealed by passing a freezing mixture 85 through a coil or equivalent freezing apparatus associated with the storage tank, and thereafter passing steam through a coil or equivalent heating apparatus associated with the said tank to fluidify again the fuel for use as such, and during these operations 90 storing the fuel under water seal which forms a layer adjacent to the top surface of the fuel and in contact therewith.

Signed at New York city in the county 95 of New York and State of New York, this 17th day of February, A. D. 1920.

LINDON WALLACE BATES.
